UNITED STATES PATENT OFFICE.

GUY L. MEAKER, OF CHICAGO, ILLINOIS, ASSIGNOR TO THE MEAKER COMPANY, OF CHICAGO, ILLINOIS, A CORPORATION OF ILLINOIS.

APPARATUS FOR ELECTROPLATING.

No. 913,747.

Specification of Letters Patent.

Patented March 2, 1909.

Application filed November 20, 1907. Serial No. 402,999.

To all whom it may concern:

Be it known that I, GUY L. MEAKER, a citizen of the United States, and a resident of Chicago, Cook county, Illinois, have invented 5 certain new and useful Improvements in Apparatus for Electroplating; and I do hereby declare that the following is a full, clear, and exact description of the same, reference being had to the accompanying drawings, and to 10 the letters of reference marked thereon, which form a part of this specification.

This invention relates to that class of electro plating apparatus set forth in my prior patent issued on the 13th day of March, 1906, 15 No. 815,027.

The object of the invention is to provide a plating apparatus through which articles to be electro plated are continuously passed during the process of plating, and which affords 20 means for rotating or turning the articles during plating to direct every portion thereof toward the anodes and to prevent uneven plating.

It is also an object of the invention to afford 25 a supporting tray which serves as the cathode element, the bottom of which is provided with a plurality of upwardly projecting conducting points with which the articles to be plated contact in traveling through the apparatus.

It is further an important object of the invention to afford an inclined cathode support for the articles to be plated and means 35 for jarring and reciprocating the same whereby the articles supported thereon are intermittently moved toward the point of discharge and to provide at said point of discharge suitable mechanism for delivering said articles from the apparatus.

It is an important object of the invention 40 to provide means for supporting the anode elements in the electrolyte whereby any anode or anodes may be swung out of the path or submerged therein, as preferred, to vary 45 the anode surface to suit the requirements of the most economical and effective use of current and materials and to provide also in connection with said anodes, supporting bars, adapted to afford suitable contacts with 50 complementary members connected with the source of current to insure maximum efficiency of the current.

It is further an object of the invention to

provide a cathode support for the articles during plating which serves to distribute the 55 same over a large surface but economizes in current and material by restricting the exposed cathode surface.

The invention consists of the matters hereinafter described and more fully pointed 60 out and defined in the appended claims.

In the drawings: Figure 1 is a fragmentary top plan view of a device embodying my invention. Fig. 2 is a longitudinal side elevation thereof. Fig. 3 is a section taken on line 65 3—3 of Fig. 1 with parts omitted. Fig. 4 is a section taken on line 4—4 of Fig. 2 with parts omitted. Fig. 5 is an enlarged fragmentary top plan view of the tray and supporting means therefor. Fig. 6 is an enlarged fragmentary section of the tray and its support. Fig. 7 is an enlarged fragmentary section of the elevator belt and a bucket thereon. Fig. 8 is an enlarged fragmentary detail of one of the supporting bars for the anodes. Fig. 9 is 75 a fragmentary side elevation illustrating one of the knife contacts of one of said anode supporting bars with the conductor. Fig. 10 is a fragmentary detail of the bearing pieces whereon the tray is supported on the shaft B. 80 Figs. 11, 12 and 13 are details of one embodiment of my invention.

In said drawings: A indicates a tank for the electrolyte. Said tank may of course be of any suitable size, form or material, but as shown, is an elongated rectangular trough 85 constructed of wood or any material not adapted to injuriously affect or be affected by the electrolyte. B indicates a transverse shaft or rod extending through the 90 sides of said tank somewhat above the bottom and affording connection for one of the conductors from the generator B' or other source of current. Slidably supported near its lower or discharge end on said shaft B is 95 a frame C comprising parallel side rails c and an upper end rail c'. Extending transversely beneath and connecting said side rails c, are bars c², which are rigidly bolted through the side rails c, as shown in Figs. 2, 100 3 and 6, and on which, adjacent each of said side members c, and extending longitudinally the frame, is secured a conductor c³, comprising a sheet or plate of suitable metal. Resting in said frame and upon said conductors c³, is a tray D, comprising as shown, 105

2

side rails d parallel with the side rails c , of the frame, and an end rail d' . The bottom of said tray comprises a sheet or sheets of metal d^2 , conveniently copper, which to 5 limit the exposed cathode surface, may be lined on the upper side with insulating material d^3 , through which project metallic pins d^4 . These are shown as rivets, rigidly secured in the sheet metal bottom of the 10 tray and the heads of which protrude above the lining, but of course, a non-conducting bottom may be used and straps or bars of metal inserted in its upper surface and connected with the conductors. Said tray is 15 rigidly secured to the side members c of the frame by means of plates d^5 , which are bolted to the rails c and engage over the side members d of the tray. The forward or receiving end of said frame and tray are supported at an elevation above the discharge 20 end. For this purpose as shown, a bracket E is rigidly secured upon each of the side walls of the tank at the front end thereof and at its upper part affords bearings for a 25 transverse shaft e , on which are journaled jar bars E' one for each side of the frame C . Rigidly secured on the forward end of said frame approximately in alignment with the side rails c , are forwardly projecting arms 30 or brackets c' , through the forwardly projecting ends of which extends a shaft e' which also extends through the lower ends of the jar bars, as shown in Figs. 2 and 5.

Journalized transversely, on the rear sides 35 of the brackets E , at the top of the tank is a driving shaft E^2 which is provided at one end with a driving pulley e^2 , adapted for engagement by a suitable driving belt and at its opposite end with a suitable pulley or 40 sprocket wheel (in this instance shown as a grooved pulley), e^3 , adapted to drive an elevator to deliver the plated articles from the machine. Rigidly secured on said driving shaft E^2 are cams e^4 one opposite each 45 jar bar as the driving shaft rotates drawing the frame and tray forwardly, and is shaped to afford a quick release at the forward limit of movement of the jar bar. For this purpose the opposite or release side for said 50 cam projection is abrupt, and to further effect quick release, the lower rear side of each jar bar is cut away just below the point of contact with said cam so that when pressed forwardly to its limit of travel, immediate and complete release follows, permitting the jar bars with the attached frame and tray to swing longitudinally the 55 tank. As shown a shaft F , extends transversely through the tank and secured thereon are strong pulling springs f , attached at their ends respectively to the jar bars and to said shaft and which act to snap the frame and tray toward the rear after 60 each slow forward movement. Pivoted 65 engaged on said shaft F is the receiving

chute f' the upper end of which rests on the periphery of said cams and is somewhat wider than the frame and tray. The lower end thereof projects over the tray and tapers to slightly less than the width of the tray 70 to insure the delivery of the articles to be plated across the entire width of the tray. As shown a strong pulling spring f^3 is secured on the end of said chute above the cams and extends obliquely downward and 75 is attached to the end of the tank as shown in Figs. 1 and 2, thus holding the upper end of the chute firmly on the cams. Said cams act to rock said chute on its shaft F , and as the projections e^5 , on the cams pass from 80 beneath the chute the spring f^3 , pulls the end thereof down upon the cams constantly jarring the chute and spilling the contents into the tray.

Rigidly secured on the under side of the 85 frame C are metallic shoes c^6 which bear on the shaft B and are of a length to permit the longitudinal reciprocation of the frame and tray before described and are conveniently provided at their front ends with hooks c^7 90 which extend beneath the shaft B . Butting blocks G are bolted one on each side of the tank and projecting inwardly into position to afford stops for the frame and tray at the rearward limit of movement. The frame 95 rails c are each provided with a stop g bolted on its rear end in position to abut the butting block G at the rearward limit of movement to suddenly stop the frame and tray when snapped back by the springs. 100

Journalized in suitable brackets H on the rear end of the tank is a shaft h , having on its outer end a grooved pulley h' , adapted to receive the driving line or belt h^2 , trained around the grooved pulley e^3 on the driving 105 shaft E^2 . Journalized transversely in the tank near the bottom thereof and parallel the shafts h is a shaft H' , and trained about said shafts h and H' is a conveyor belt h^3 having buckets h^4 rigidly secured thereon by 110 riveting or other suitable means. Each of said buckets is perforated in its bottom to permit the escape of the electrolyte and may be constructed of sheet metal, fiber or any suitable material. 115

Journalized on the shaft B is a discharge chute I , at the inner or receiving end of which is provided as shown a strap of metal i , which extends around the bottom and sides thereof and is apertured to receive and pivotally engage on said shaft B . The discharge end of said chute I extends into position to be successively engaged by the buckets h^4 , on the elevator. As the elevator is slowly driven by the belt h^2 the discharge end of said chute is slowly lifted until the chute is about horizontal at which point it slips off the bucket and falls until engaged to be again lifted by the next succeeding bucket, thereby jarring its contents into the buckets 125 130

of the elevator from whence they are of course delivered from the tank.

As shown, conducting cables B^2 are secured on said conducting shaft B and are 5 electrically connected with the metallic conductor c^2 in the frame or if desired, may be connected immediately with the metallic bottom of the tray.

Extending longitudinally along the top of 10 the tank on one of the side walls is a conductor k , and as shown, consisting of a flat strap or plate of metal and hinged on one of said side walls are supporting bars K for the anodes. These as shown in Figs. 1, 2 and 3 15 are bars of wood or any suitable material each having on the under side thereof a bus bar comprising a strap of suitable conducting material k' which rests on the strap k , adjacent the hinge, and at the opposite side of 20 the tank rests on a similar conductor k^2 . Said conductors k and k^2 are electrically connected by means of a bus bar k^3 which extends across the tank and with which one of the leads from the source of current is connected. Suitable bolts k^4 extend through 25 said bar K and bus bars k' and rigidly engaged thereto at the lower ends thereof transversely the cathode tray are the anodes K' , which may be of any desired 30 number and are conveniently of the metal it is desired to plate upon the articles treated. Said supporting bolts k are progressively longer toward the rear end of the tank so that said anodes are all supported at the 35 same distance above the tray.

From the construction described it is obvious that any of said supporting bars K with its anode K' may be swung upwardly 40 out of the electrolyte for adjustment or removal of the anode or to reduce the plating surface and control the current density. This of course, breaks the circuit through such bus bars without disturbing the other anodes or interfering with the operation of 45 the apparatus and affords an important means for regulating the operation. To insure a perfect contact when in operation the construction shown in Figs. 8 and 9 is desirable. For this the free end of said bar K is 50 provided with a metallic contact piece k^5 rigidly bolted thereto and flanged under the same to engage the bus bar k' and provided with a longitudinally extending vertically set web or knife k^6 . This engages wedgily between 55 contact plates k^7 which are integrally connected with a base member k^8 bolted or otherwise secured to the conductor k^2 .

The operation is as follows: Sufficient of the electrolyte having been placed in the 60 tank A to submerge the tray and the anodes, the articles to be plated are delivered into the tray slowly by means of a chute f' and the current is turned on, and the driving shaft actuated from any suitable source of 65 power. The rotation of said shaft with its

cams serves successively to elevate and to drop the forward end of the chute f' upon the cam, the spring, of course, pulling the end down with considerable force upon the lower portion of the cam and jarring the 70 articles into the tray. The cams also press the jar bars forwardly until the projection e^5 passes the contact points on the jar bars whereupon the springs f pull the jar bars with the frame and tray supported thereon 75 rearwardly of the tank with some violence until stopped abruptly, thus tending to jar and deliver or roll the articles within said tray toward the lower or discharge end thereof. To facilitate the rolling movement 80 of said articles the bottom of said tray is arranged in successive steps or ledges as shown in Fig. 2 and the metallic contacts whether pins or strips are so disposed that the articles being treated are at all times in contact with 85 one or more thereof. The elevator is driven continuously from the driving shaft and as the articles plated successively fall into the chute I , they are moved rearwardly into the buckets by the movement of said chute, 90 the rear end of which is raised slowly on one elevator bucket to approximately horizontal position when the bucket passes from beneath the same permitting the end of the chute to drop upon the next bucket, and 95 below horizontal, thus jarring the articles rearwardly on said chute and into the elevator.

Of course, overlapping metallic plates D^2 of copper or other suitable metal either with 100 or without its surface covered or partly covered with insulating material, may be employed for the bottom of the tray and in either case after the cathode surface or surfaces have accumulated a considerable coating of the plating metal the cathodes may be removed and fresh plates substituted and the plates so coated or partly coated may be utilized as anodes until the surplus material has plated off, as shown in Figs. 11 to 13. 105 The plates if so used, are of course provided with an aperture at each end which is covered by the side rails d of the tray when used as cathodes but which receive the supporting rods k^4 when used as anodes. In this 110 way all the plating metal is utilized and inconvenience and loss from the accumulation of the plating metal upon the cathodes is avoided.

The anodes in the construction described 120 are capable of being removed independently from the electrolyte and any or all of the same may be swung upwardly, each bus bar breaking the circuit for its anode, when lifted. This enables the plating surface and 125 current density to be at all times perfectly controlled and together with the construction of the cathode elements greatly economizes in current and material.

Obviously many details of the construction 130

may be varied without departing from the principles of this invention. I therefore do not purpose limiting this application for patent otherwise than necessitated by the 5 prior art.

I claim as my invention:

1. An electro plating apparatus embracing a tank to contain the electrolyte, a cathode element therein consisting of a tray for supporting the articles to be plated and open at the discharge end, mechanism for vibrating the tray and a butting block against which the tray strikes at one limit of movement.
10. 2. An electro plating apparatus embracing a tank to contain the electrolyte, a cathode element therein consisting of a tray for supporting the articles to be plated and open at the discharge end, mechanism for vibrating the tray and a butting block rigidly secured to the tank and against which the tray strikes at one limit of movement.
15. 3. An electro plating apparatus embracing a tank to contain the electrolyte, an inclined open ended tray for supporting the articles to be plated, a bottom therefor of conducting material affording the cathode element, mechanism for vibrating the tray longitudinally of the tank and a rigidly secured butting block against which the open or discharge end of the tray strikes at one limit of movement.
20. 4. An electro plating apparatus embracing a tank to contain the electrolyte, a source of current, a submerged tray inclined toward its open discharge end, a downwardly stepped conducting bottom for said tray electrically connected with the source of current and affording the cathode element, means vibrating and jarring said tray to move its contents to discharge position, anodes connected with the source of current, an open ended discharge chute supported to swing vertically at its discharge end, an elevator positioned to actuate the discharge chute and to receive the plated articles therefrom, and means actuating the same.
25. 5. An electro plating apparatus comprising a tank to contain the electrolyte, a source of current, a tray inclined toward and open at its discharge end, a downwardly stepped conducting cathode bottom for said tray, means jarring said tray, anodes connected with the source of current and supported above the tray in the electrolyte, a discharge chute supported to receive the plated articles from the tray and to swing at its discharge end, and means adapted to actuate the chute and to deliver the plated articles from the tank.
30. 6. An electro plating apparatus comprising a tank to contain the electrolyte, a source of current, a tray inclined toward and open at its discharge end, and extending longitudinally in said tank, a downwardly stepped
- conducting bottom for said tray connected with the source of current, means reciprocating said tray in the tank to afford slow forward movement and faster rearward movement, a butting block adapted to abruptly stop the tray at one limit of its movement, anodes connected with the source of current and supported in the electrolyte and above the tray, an open ended discharge chute supported to swing vertically at its discharge end, an elevator positioned to actuate the chute and receive the plated articles therefrom and means actuating the elevator.
35. 7. An electro plating apparatus comprising a tank to contain the electrolyte, a source of current, an open ended cathode tray for supporting the articles to be plated, a vibrating chute supported at the receiving end of the tray to distribute the articles to be plated therein, an open ended vibrating chute at the rear or discharge end of the cathode tray to receive the plated articles therefrom, an elevator adapted to vibrate said discharge chute and acting to deliver the plated articles from the tank, independently supported anode elements adapted to be submerged in the electrolyte, means vibrating said tray to deliver the articles to be plated along the same and means adapted to abruptly arrest the vibrations to accelerate the travel of the articles on the tray.
40. 8. An electro plating apparatus comprising a tank containing an electrolyte, a source of current, a cathode tray for supporting the articles to be plated and having a discharge opening and connected in the current, a vibrating chute supported at the receiving end of the tray to distribute the articles to be plated therein, an open ended vibrating chute supported to receive the plated articles from the tray, means adapted to vibrate said discharge chute and deliver the plated articles from the tank, independently supported anode elements normally submerged in the electrolyte at a uniform distance above the tray, each hinged to swing upwardly out of the electrolyte.
45. 9. An electro plating apparatus comprising a tank to contain an electrolyte, a source of current, an open ended cathode tray for supporting the articles to be plated and connected with said source of current, an inclined vibrating chute supported at the receiving end of the tray to distribute the articles to be plated therein, means actuating said chute and said tray, an open ended vibrating chute at the rear or discharge end of the cathode tray to receive the plated articles therefrom, a bucket elevator adapted to vibrate said discharge chute to deliver the plated articles from the chute into its buckets, anode elements supported independently in the electrolyte at a uniform distance from the tray and connected with the other lead

from said source of current and means acting to abruptly arrest the movement of the tray at the rearward limit of its travel.

10. An electro plating apparatus embracing a tank containing an electrolyte, a source of current, a cathode element adapted to support the articles to be plated, anode elements embracing bus bars hinged at one side of the tank, an anode rigidly but detachably secured to each, a conductor on one side of the tank connected with the other lead from the source of current and adapted to be engaged by the bus bars when the anodes are submerged in the electrolyte.

15. 11. An electro plating apparatus embracing a tank to contain the electrolyte, a source of current, a cathode element connected with one lead from said source and adapted to support the articles to be plated, bus bars hinged at one side of the tank, an anode rigidly secured to each, a conductor at one side of the tank adapted to be engaged by the bus bars when the anodes are submerged in the electrolyte and connected with the other lead from said source and means mechanically actuating the articles to be plated through and out of the apparatus.

12. An electro plating apparatus embracing a tank to contain an electrolyte, a source of current, a tray, a sectional stepped bottom in said tray affording metallic surfaces comprising the cathode elements and adapted to support the articles to be plated, bus bars pivotally secured at one side of the tank, an anode rigidly secured to each, a conductor on one side of the tank adapted to be engaged by the bus bars when the anodes are submerged in the electrolyte and leads from the source of current connected with said cathode elements and with the conductor to the bus bars and means jarring the tray.

13. In an electro-plating apparatus a movably supported cathode tray embracing side and end members, a sectional bottom and strip of conducting material extending longitudinally of the bottom and electrically connected therewith.

14. In an electro-plating apparatus a cathode tray embracing a sectional bottom comprising independently removable sheets of conducting material and said sheets overlapped forming a stepped bottom.

15. In an electro plating apparatus a cathode tray embracing side members and a front end rail, a sectional bottom secured to said side members and end rail and embracing metallic sheets, upwardly projecting metallic conductors engaged thereon and non-conducting material covering each sheet and through which said studs project.

16. In an electroplating apparatus a cathode tray having a sectional bottom, having a large supporting area relative its conducting area.

17. In an electro plating apparatus a cathode tray having a sectional bottom having a large supporting area relative its conducting area and means jarring the tray to deliver the articles therefrom when plated.

18. In an electro plating apparatus a vibrating cathode tray embracing a frame of non-conducting material open at the rear end and supported to incline toward said open rear end, conducting plates supported on the frame approximately horizontally to afford a stepped bottom for said tray mechanisms for vibrating and for jarring said tray and pivoted means adapted to receive the articles from said tray.

19. In an electro plating apparatus a vibrating cathode tray to support the articles to be plated embracing a frame of non-conducting material open at and inclining toward the rear end, independently removable conducting plates secured on said frame approximately horizontally to afford a stepped bottom for said tray, a mechanism adapted to swing said tray slowly forward and rapidly rearwardly toward its open end and means abruptly arresting such rearward movement thereby acting to roll the articles supported in the tray along and from the same.

20. In an electro plating apparatus a vibrating cathode tray embracing a frame of non-conducting material open at the rear end and supported to incline toward said end, independently removable cathode elements supported approximately horizontally on said frame, to afford a stepped bottom for said tray, mechanism adapted to swing said tray slowly in one direction and rapidly in another and a butting block positioned to jar the tray thereby acting to roll the articles supported in the tray toward the discharge position.

21. In a device of the class described the combination with a cathode element for supporting the articles to be plated of a chute supported to receive said articles therefrom, and pivoted near its end below said tray, a positively driven bucket elevator positioned to engage with successive buckets, the discharge end of the chute to successively lift the same to horizontal and to release to drop the same below horizontal thereby jarring the plated articles into the buckets.

22. In a device of the class described the combination with a cathode element for supporting the articles to be plated of a chute supported to receive said articles therefrom and pivoted below said cathode and positively driven mechanism adapted to swing said chute to successively lift the same to horizontal and drop the same below horizontal and acting to deliver the plated articles from the machine.

23. In a device of the class described the

- combination with the tank for containing the electrolyte, of a source of current, a cathode element connected with one lead therefrom, a conductor disposed on one side 5 of the tank and connected with the other lead from the source of current, a plurality of bus bars hingedly supported on one side the tank and adapted when in supporting position to engage said conductor on the tank 10 and an anode element removably supported on each bus bar and adapted to be submerged in the electrolyte or to be swung upwardly out of the same by means of said bus bar.
- 15 24. In an electro plating apparatus a cathode tray having large supporting area and small conducting area and anodes hinged above the same and adapted independently to be swung out of circuit.
- 20 25. An electro plating mechanism embracing a cathode tray affording a large supporting surface of non-conducting material, conducting contact pieces disposed over said surface to transmit current to the articles in the tray and independently movable anode elements adapted to be swung singly 25 out of circuit.
26. In a machine of the class described a reciprocating cathode tray, means for delivering the articles to be plated thereon, mechanism for actuating said means independently of the tray and means connected with the delivery means at the rear end thereof to aid in jarring said delivery means.
- 30 27. In a machine of the class described means for supporting articles to be plated, mechanism for actuating the same to advance said articles, means for delivering articles upon the supporting means, mechanism for elevating and depressing one end of said delivering means to jar the articles upon the supporting means and a spring adapted to aid in depressing the end of said 35 delivering means.
- 40 28. In a plating machine a reciprocating tray, oscillating means for delivering articles upon the tray, mechanism for elevating one end of the delivering means, means for depressing said end of the delivering means and mechanism for actuating the tray to advance the articles therealong.
- 45 29. In a plating machine a cathode tray, means adapted to deliver articles thereto, mechanism for actuating said means to deliver articles upon the tray and actuating the tray to advance the articles therein after each delivery and means coacting with the aforesaid actuating mechanism for operating the delivering means.
- 50 30. In a machine for plating articles a supporting cathode element for intermittently advancing said articles, means for intermittently delivering the articles upon said supporting element and coacting mechanisms, one for elevating the delivering means and 65 the other for quickly depressing the same for actuating said delivering means to deliver the articles to the cathode element prior to each advancement of the articles upon the cathode element.
- 70 31. In a machine of the class described a cathode element movable to advance articles therealong, means for delivering articles upon said cathode element while said element is at rest and a receiving tray pivoted at the delivery end of the cathode element.
32. In a device of the class described a cathode element for supporting articles and movable to advance said articles, means movable independently of said cathode element for delivering the articles to the cathode element, means for limiting the rearward movement of the cathode element and means pivotally supported to receive the plated articles from the cathode element.
- 80 33. In a machine of the class described a reciprocating, vibrating cathode element for supporting and advancing articles to be plated, an oscillating device for delivering articles thereto and an oscillating device for receiving the articles from the cathode element.
- 85 34. In a machine of the class described a reciprocating, vibrating cathode element for supporting and advancing articles to be plated, an oscillating device for delivering articles thereto, an oscillating device for receiving the articles from the cathode element and mechanism adapted to oscillate said receiving device for automatically removing the plated articles therefrom.
- 90 35. In a device of the class described a tray for supporting and advancing articles to be plated, and an oscillating device at each end thereof, one to deliver the articles upon the tray and the other to receive the articles from the tray.
- 105 36. In an electric plating machine of the class described a tank, a reciprocating cathode tray therein for supporting articles, means for actuating the tray to roll the articles therealong and constantly exposing different faces of the articles, buckets for automatically delivering the articles from the machine and permitting the electrolyte to return to said tank and mechanism actuated by each bucket to deliver a quantity of articles to the next succeeding bucket.
- 110 37. In an electro-plating machine a tank, a tray therein for supporting articles, means for rolling the articles therealong, means for delivering the articles from the tank and means interposed between the tray and delivering means and automatically actuated to convey the articles from the tray to the delivering means.
- 115 38. In an electroplating machine a cathode tray, a pivoted element for receiving articles

therefrom and an elevator comprising buckets, each bucket adapted to swing the said element on its pivot to fill the same with articles and each bucket apertured to permit 5 the electrolyte draining therefrom.

39. In an electro-plating machine the combination with the tank for containing the electrolyte of mechanism for plating the articles in said tank and means for delivering 10 the articles from the tank apertured to permit the electrolyte draining back into the tank.

40. In a machine of the class described the combination with a tank for containing the electrolyte, a cathode element immersed in 15 the electrolyte and anode elements attached to the tank and adapted each to be immersed in the electrolyte or adjusted out of the electrolyte.

20 41. In a machine of the class described the combination with a tank for containing the electrolyte, a cathode element immersed in the electrolyte, anode elements attached to the tank and adapted each to be immersed in 25 the electrolyte or adjusted out of the electrolyte, a pivoted chute above the cathode element and mechanism adapted to vibrate the same and the cathode element.

42. In a machine of the class described a 30 tank for holding the electrolyte, a cathode element immersed in said tank, supporting bars pivoted to the tank and anode elements rigidly secured to said bars and adapted to be removed therefrom.

35 43. In a machine of the class described a tank for holding the electrolyte, a cathode element immersed in said tank, anode elements pivoted to the tank adapted to be adjusted into or out of said tank, means for automatically delivering articles to be plated upon the cathode element, and means pivoted at the end of the cathode element to receive the articles therefrom.

44. In a machine of the class described a 45 tank for holding the electrolyte, a cathode element immersed in said tank, anode elements pivoted to the tank adapted to be adjusted into or out of said tank, means for automatically delivering articles to be plated 50 upon the cathode element, means pivoted at the end of the cathode element to receive the articles therefrom, electric cables connected with the cathode element and electrically connected with a source of electric supply 55 and means adapted to connect all of the

anode elements in the tank with said source of electric supply.

45. In an electro-plating machine a tank for the electrolyte, an inclined cathode tray therein having an electrically conducting 60 stepped bottom, independent anode elements pivotally supported to swing into the tank and each positioned an equal distance from the cathode tray when in the tank.

46. In an electro-plating machine a tank 65 for the electrolyte, an inclined cathode tray therein having an electrically conducting stepped bottom, independent anode elements pivotally supported to swing into the tank, each positioned an equal distance from 70 the cathode tray when in the tank, means electrically connecting the cathode with a source of electric supply, and a strip of electrically conducting metal secured to the tank adapted to supply current to each anode element when adjusted into the tank. 75

47. In an electro-plating machine a tank for containing the electrolyte, a cathode element in the tank for supporting and advancing the articles to be plated, an electrically 80 conducting bar secured to each side member of the tank, a conductor connecting said bars, insulating bars each pivoted at one end to one of the side members of the tank, anodes secured thereto of plating metal and a bar of 85 conducting metal secured to each insulating bar in position to contact said bars secured to the top of the side members and electrically connected with the respective anode.

48. In a machine for plating metal a 90 cathode element having a bottom of insulating material and electrically conducting elements projecting through said insulating bottom.

49. In a machine for plating with metal a 95 cathode element comprising side members, an insulating bottom sheet, a conducting sheet below the insulating sheet, conducting points extending through the insulating bottom at suitable distances apart and electrically connected with the conducting sheet, 100 and means connecting the conducting sheet with a source of electrical supply.

In testimony whereof I have hereunto subscribed my name in the presence of two sub- 105 scribing witnesses.

GUY L. MEAKER.
